TOBACCO SUPPLY MEANS FOR CIGARETTE MACHINES

Willi Friedrich Schneider, Kotitz, near Coswig, Germany, assignor to the firm "Universelle" Cigarettenmaschinen-Fabrik J. C. Muller & Co., Dresden, Germany

Application July 29, 1929, Serial No. 381,826, and in Germany August 7, 1928

2 Claims. (Cl. 302—28)

The subject of the present invention is a means of supplying a number of cigarette machines with tobacco by means of a single pneumatic supply conduit in such manner that the tobacco is automatically supplied to those cigarette machines of which at any time the tobacco supply is exhausted. To this end each cigarette machine is connected with an indicating device coming into or set in operation on exhaustion of the tobacco supply by a control valve associated with the cigarette machine in question and interposed in the continuously operating feed conduit in such manner that the supply of the tobacco to this cigarette machine continues until on exhaustion of the tobacco supply of another associated cigarette machine, transfer of the supply to this machine is effected.

In this manner the tobacco is fed continuously by the common feed conduit, but is delivered always to that cigarette machine in which the tobacco supply is already exhausted or has been consumed to a predetermined extent. The control may be wholly automatic or semi-automatic by providing in front of each cigarette machine a tobacco collecting hopper which is preferably connected to the usual dust separating device and is connected with the tobacco spreader in such manner that by opening the closing valve or the like of the collecting hopper an electric circuit is closed which actuates an indicating device, by which the supply valve in the pneumatic feed line for the tobacco to the collecting hopper in question is controlled.

The feed valves interposed in the pneumatic feed line consist of closing flaps which are arranged as plates at the branches from the main feed line to the separate cigarette machines and are held under spring control in such manner that they close the corresponding line, while an electromagnet influences a tension member which, on the electromagnet being excited and overcoming the tension of the spring, moves the valve flap into the position where the extension of the main feed line is closed and the branch is opened.

The invention is illustrated by way of example in the accompanying drawing, in which Fig. 1 is a side elevation and Fig. 2 a plan view, while Fig. 3 shows an enlarged detail of the juncture of the main tobacco feed conduit and one of the branch lines leading therefrom.

Referring to the drawing, A, B, C indicate three cigarette machines disposed one behind the other and adapted to be supplied by a common pneumatic feed conduit a . The compressed air sup-

ply is provided by a blower b and the tobacco is delivered to the inlet c .

In front of each cigarette machine is located a dust separator d of known construction, each dust separator being connected by a line e branching off at an inclination from the main feed line a of the pneumatic tobacco supply. The compressed air loaded with dust passes from the dust separator into the common delivery pipe f through a connecting branch g .

Between each dust separator and the usual tobacco spreaders of the separate cigarette machines is provided a collecting hopper h which is connected to the dust separator and is supplied thereby with clean tobacco, while a closing flap i permits the transfer of the tobacco from the collecting hopper h into the tobacco spreader of the associated cigarette machines only after being moved into the open position. The dimensions of the collecting hopper h are so chosen that the tobacco supply of the filled collecting hopper corresponds to the usual quantum of the tobacco spreader.

At the point where the branch e leads from the main feed line a , indicated in Fig. 3, there is provided a flap valve k which is arranged as a plate in such manner that it may turn about a pivot l and either cut off the extension of the main feed line a (in the position indicated by full lines) or cut off the branch e (see the position indicated by the dotted line).

To a rearwardly extending portion m of the flap valve k is attached a tension spring n tending to pull the flap continuously into the position to close the branch line e . With the extension m is connected a longitudinally movable connecting rod o which terminates in the armature p of an electro-magnet q . When the electro-magnet is excited it attracts the armature p and turns the flap valve k against the action of the spring n into the position to close the extension of the main feed line a .

Each closing flap i of each collecting hopper h is formed as a contact so that on moving the corresponding closing flap i into the open position an electric circuit is closed through the conductors r , s , each conductor r , s acting on an indicating device as is usual in electric bell annunciators or the like, and in which by the dropping of a flap an indicator is exposed to view. On this indicator appears a number or the letter, A, B, C, of the cigarette machine in question.

With each indicating device is connected a switch t . On moving over the switch lever a circuit is closed which excites the electromagnet q

associated with the cigarette machine in question, so that the corresponding valve closing flap *k* is moved in a direction such that the tobacco supply is delivered to the corresponding branch *e*, to 5 its dust separator or to its collecting hopper *h*.

Care must be taken that the tobacco spreaders of the separate cigarette machines are kept supplied with tobacco and the corresponding collectors *h* are filled. As soon as the filling of the 10 tobacco spreader is necessary in one machine, the corresponding flap *i* is opened. The tobacco supply of the corresponding hopper is thus emptied into the tobacco spreader and at the same time the corresponding valve flap is operated by 15 the electromagnet, so that a further supply of tobacco is delivered to the collecting hopper *h*. The arrangement can easily be such that one of the cigarette machines is always in a condition such that subsequent filling of the tobacco 20 is necessary.

The operation can be carried out automatically or semi-automatically. It is possible obviously to control the flaps *i* automatically in conjunction with the control of the flap valves *k*. More- 25

over the flaps *i* can be automatically opened as soon as the tobacco supply of the tobacco spreader falls below a pre-determined amount.

I claim,

1. In a device for supplying tobacco to a plurality of cigarette machines disposed one behind the other, a common feed inlet, a common pneumatic feed conduit for said machines leading from said inlet, a dust separator in front of each of said machines, a branch conduit leading from 80 said machines, a branch conduit leading from 85 said common feed conduit to each dust separator, a common dust delivery pipe, branch pipes leading from each separator to said common dust delivery line, a collecting hopper between each dust separator and machine, a valve at the bottom of each collecting hopper, a valve at the juncture of each branch feed line and main feed 90 line to divert the feed of the tobacco in the main feed line to the respective branch feed line and means for operating said last named valve. 95

2. The combination as set forth in claim 1, in which the valve at the bottom of each collecting hopper consists of a flap.

WILLI FRIEDRICH SCHNEIDER.
